(57) **CLAIM**

The ornamental design for a pool hand rail, as shown and described.

DESCRIPTION

FIG. 1 is a right side elevation view of a pool hand rail, showing, in particular, the ornamental design thereof. It will be understood that a left side elevation view will be a mirror image of the right side elevation view;

FIG. 2 is a front elevation view of the pool hand rail of FIGS. 1, 6, and 8;

FIG. 3 is a rear elevation view of the pool hand rail of FIGS. 1, 6, and 8;

FIG. 4 is a top plan view of the pool hand rail of FIGS. 1, 6, and 8;

FIG. 5 is a bottom plan view of the pool hand rail of FIG. 1; FIG. 6 is a right side elevation view of a second embodiment of the pool hand rail, showing, in particular, the ornamental design thereof. It will be understood that a left side elevation view will be a mirror image of the right side elevation view;

FIG. 7 is a bottom plan view of the pool hand rail of FIG. 6; FIG. 8 is a right side elevation view of a third embodiment of the pool hand rail, showing, in particular, the ornamental design thereof. It will be understood that a left side elevation view will be a mirror image of the right side elevation view; and,

FIG. 9 is a bottom plan view of the pool hand rail of FIG. 8. The stiles of the pool hand rail have been broken near the ends to indicate indeterminate length.
